MAX SHERMAN

A. Engel
ATTY.

UNITED STATES PATENT OFFICE.

MAX SHERMAN, OF BROOKLYN, NEW YORK, ASSIGNOR TO BLUE RIBBON SILVER MANUFACTURERS, INC., OF NEW YORK, N. Y., A CORPORATION OF NEW YORK.

DESIGN FOR A VASE.

59,036.

Specification for Design.

Patented Sept. 13, 1921.

Application filed March 16, 1921. Serial No. 452,765. Term of patent 7 years.

To all whom it may concern:

Be it known that I, MAX SHERMAN, a citizen of the United States, residing at Brooklyn, in the county of Kings and State of New York, have invented a new, original, and ornamental Design for Vases, of which the following is a specification, reference being had to the accompanying drawing, forming part thereof.

The figure is a perspective view of a vase showing my new design.

I claim:

The ornamental design for a vase as shown.

MAX SHERMAN,
